Elvie Bauer, 9100 Long Lane,
Cincinnati, Ohio 45231

Filed Feb. 10, 1967, Ser. No. 5,768

Term of patent 14 years

(Cl. D26—10)

Fig 1

Fig 2

Fig 3

FIGURE 1 is a top plan view of the electric fence wire insulator embodying my new design; and

FIGURE 2 is a front elevational view of the electric fence wire insulator; and the rear of the electric fence wire insulator, when taken from FIGURE 2, is substantially plane, except for the apertures as indicated; and

FIGURE 3 is a side elevational view thereof.

The fragmentary broken line showing of an electric fence wire is for illustrative purposes only.

I claim:

The ornamental design for an electric fence wire insulator, as shown and described.
